REFRIGERATING APPARATUS OF THE
COMPRESSION TYPE

Rudolf Hintze, Berlin-Charlottenburg, Germany,
assignor to Patentverwertungs-Gesellschaft
mit beschränkter Haftung "Hermes", Berlin,
Germany, a corporation of Germany

Application March 16, 1939, Serial No. 262,143
In Germany March 17, 1938

10 Claims. (Cl. 62—115)

My invention relates to improvements in refrigerating apparatus of the compression type, in particular to refrigerators having a hermetically-sealed motor-compressor set.

5 It is known to simplify the manufacture of individual refrigerator elements, such as the condenser or the evaporator, by welding two corrugated metal sheets together in face-to-face relationship so that the condenser or evaporator conduits are formed by the corrugations. According to the prior art these individual condenser or evaporator elements are connected with each other and with the compressor by additional pipe connections.

15 An object of the present invention is to simplify the construction and manufacture of refrigerating apparatus having an hermetically-sealed motor-compressor set by reducing the number of individual elements to be assembled.

20 Another object, more particularly, is to eliminate at least part of the separate pipe connections heretofore necessary for interconnecting the various elements of a compression refrigerator system. An object also is to increase the amount of 25 sheet metal work relative to other manufacturing operations required for compression refrigerators, so as to reduce a considerable portion of the manufacturing process to the stamping, bending, and welding of a few sheet metal pieces. Other objects of my invention deal with the design and 30 arrangement of the compressor, condenser and evaporator elements relative to one another and relative to a refrigerator cabinet so as to obtain a simple yet reliable and thermally economical 35 construction.

According to my invention, the housing, which hermetically encloses the motor-compressor set of a refrigerating apparatus, is at least partly formed of an indented and corrugated metal sheet 40 which forms also part of a sheet metal condenser. According to the further invention, a considerable portion of the housing, the condenser, the evaporator and at least part of the interconnecting conduits are formed by indentations and corrugations of a single pair of metal sheets welded together in face-to-face relationship.

These and other features of my invention will become apparent from the following description of the embodiments diagrammatically illustrated 45 in the drawings in which—

Fig. 1 shows a part-sectional side elevation of a cabinet refrigerator according to the present invention, while

Fig. 2 shows a side elevation and Fig. 3 a front elevation of a sheet metal structure from which

the refrigerating system proper of the embodiment of Fig. 1 is produced by bending the sheet pairs at the two places indicated in Figs. 2 and 3 by lines *a—a* and *b—b*.

Fig. 4 illustrates another embodiment by a 5 part-sectional side view, and

Figs. 5, 6 and 7 exemplify a third embodiment by a front elevation, a sectional top view and a sectional side elevation respectively.

Referring to Fig. 1, 60 is the cabinet of a domestic refrigerator, and 61 the cabinet door. The cabinet is supported by four legs 62 so as to provide space for the motor-compressor set below the cabinet. 1 denotes the driving motor of the set, 2 the piston compressor driven by the 10 motor 1. The motor-compressor set is arranged in a housing 6 attached to the leg structure of the refrigerator cabinet and is suspended by means of springs 4 from brackets 5 secured to the housing 6. The housing has a cover portion 15 7 so as to hermetically seal the motor-compressor set. To the motor shaft is secured an oil pump 8 which forces the lubricant contained in the lower part 9 of the cover 7 to the points of the set to be lubricated. 10 denotes a valve operating 20 in response to the oil pressure. The valve establishes a communication between the suction side and the pressure side of the compressor until a given oil pressure is attained and thereby facilitates the starting of the refrigerating apparatus. This construction of the motor-compressor set is mentioned for illustrative purposes only. Motor-compressor sets of this type are described more in detail in my U. S. Patent No. 2,164,405 and do not form an essential part of 25 the present invention as any other sealed motor-compressor type may also be used.

11 denotes the condenser of the refrigerating apparatus and 12 the evaporator. 13 is a collecting vessel which may contain a regulating 30 valve, for instance a float-controlled valve, for controlling the supply of liquid refrigerant to the evaporator. A suction conduit 14 (Fig. 3) connects the evaporator 12 with the compressor. The compressed refrigerant leaves the compressor 45 through a pressure conduit 15, passes into the air-cooled condenser 11, thence through a conduit 16 to the vessel 13, and then through a conduit 17 into the evaporator. The arrangement thus includes a complete refrigerating circulation system.

The evaporator 12, the condenser 11, the vessel 13, and the conduits 14, 15 and 16, are all formed by indentations and corrugations of a single pair of metal sheets 18 and 19 placed in 50 55

- face-to-face relationship and secured together around their edges by welding. The sheet 18 forms at the same time also the cover 7 of the enclosure for sealing the motor-compressor set.
- 5 The sheets 18 and 19 are bent when welded together about the bending edges *a-a*, *b-b* into the form shown in Fig. 1, so that in the ready-assembled refrigerator, the motor-compressor set lies underneath the cooling chamber and the 10 evaporator 12 in the upper portion of the cooling chamber, whereas the condenser 11 extends along the rear wall of the refrigerator. 20 denotes an ice tray placed on the plate-shaped evaporator. 21 and 22 (Fig. 3) are recesses cut 15 out of the sheets 18 and 19 between the sheet sections forming the condenser 11 and the evaporator 12. These recesses reduce the metallic cross section of the sheet pair and thus prevent an undesirable transfer of heat from the condenser 11 to the evaporator 12. 23 (Fig. 1) denotes a plug consisting of insulating material which when assembling the refrigerator is inserted in an opening of the rear wall of the cabinet together with the sheet metal structure.
- 25 Fig. 4 shows a similar embodiment of the invention and denotes corresponding parts by the same reference numerals as in Figs. 1 to 3. The embodiment of Fig. 4 differs from that shown in Fig. 1 in that the pair of sheets 18 and 19 is bent 30 only once, namely about a bending edge corresponding to line *b-b* in Figs. 2 and 3, so that the cover 7 of the motor-compressor set lies substantially in the same plane as the condenser 11. Accordingly, the shaft of the motor-compressor 35 set is horizontal in contrast to the vertical shaft arrangement of Fig. 1.
- In Figs. 5 to 7, 31 denotes the driving motor and 32 the piston compressor of the motor-compressor set. The motor casing 33 is provided with 40 projections 34 formed of angle iron which are supported by coil springs 35 bearing against angle irons 36 secured to the housing 63 of the motor-compressor set. The housing 63 is formed by indentations of two metal sheets 41 and 42 sealed 45 face-to-face together. Other indentations of the metal sheets form the condenser and other elements to be later described. The lower end of the perpendicular motor shaft 37 is designed as an oil pump 38 as described in my aforementioned 50 patent. This oil pump projects into the oil sump at the bottom of the motor-compressor housing. A conduit 49 and a sinuous winding 50 connect the oil pump 38 with an inlet opening 51 at the top of the housing 63. The lubricant thus is 55 cooled in winding 50 before it reaches the moving parts to be lubricated. Due to this circulation of the oil, the heat developed inside the motor-compressor housing is dissipated to the sheet metal walls 41, 42 which are in direct contact 60 with the cooling air. The condenser consists of a laterally extensive vessel 40 of flat shape surrounding the housing 63 of the motor-compressor set. The bottom portion of the condenser 40 opens into a chamber 43 for collecting the liquefied refrigerant. A conduit 44 consisting of a capillary tube with helical portions 45 and 46 connects the collecting chamber 43 with the evaporator 47 (Fig. 7). A suction conduit 48 connects the evaporator 47 with the compressor.
- 70 In the embodiment shown in Figs. 5 to 7, the housing 63, the condenser 40, the condensate collecting chamber 43 and the oil circulating conduits 49 and 50 are all formed by indentations of the two metal sheets 41 and 42. Only the evaporator 47 and the two conduits connecting the

evaporator with the sheet metal structure consist of separate elements. The evaporator 47 according to Fig. 7 is secured to a heat insulating insert 64 of the cabinet wall 65.

When welding the two metal sheets forming the motor-compressor housing as well as the condenser and other elements according to the invention, it suffices as a rule to weld the sheets around their outer edges and at some intermediate not-indented places, for instance as indicated in Figs. 3 and 5 by broken lines.

As exemplified by the above-described embodiments, the invention allows producing at least a substantial portion of the circulation system of a compression refrigerator from a single pair of indented metal sheets. A considerable part of the manufacturing thus can be done by sheet metal work such as stamping and pressing. The assembling of the refrigerating systems is simplified and limited to a small number of separate elements. As a great number of the operating vessels and conduits of the circulation system are formed by the metal sheets and thus automatically brought into proper relationship and connection with one another, the manufacture of refrigerators according to the invention is less exacting and involves fewer sources of possible faults than the manufacture of the known constructions. The invention, therefore, is especially advantageous for mass production.

I claim:

1. In a refrigerating apparatus of the compression type having a motor-compressor set sealed in a housing and connected with a condenser conduit system and an evaporator conduit system, said housing and at least one of said conduit systems being formed by indentations of a single pair of metal sheets sealed face-to-face together.

2. In a refrigerating apparatus of the compression type having a compressor sealed in a housing and a condenser conduit system connected with said compressor, in combination, said condenser comprising two corrugated metal sheets sealed face-to-face together so as to form the condenser conduits between said sheets, and said compressor housing and one of said metal sheets consisting of a single sheet metal piece.

3. In a refrigerating apparatus of the compression type having a motor-compressor set sealed in a housing, a condenser, an evaporator, and interconnecting conduits, a single pair of metal sheets sealed together in face-to-face relationship and having indentations and corrugations forming said housing, said condenser, said evaporator, and said interconnecting conduits.

4. In a refrigerating apparatus of the compression type having a motor-compressor set sealed in a housing, a condenser, an evaporator, and interconnecting conduits, a single pair of metal sheets sealed together in face-to-face relationship and having indentations and corrugations forming a substantial portion of said housing, said condenser, and said evaporator, said condenser and said evaporator being arranged in two different sections of said pair of sheets, said pair being bent at a right angle so as to have said sections in planes perpendicular to each other.

5. In a cabinet refrigerator having a cooling chamber, a motor-compressor set hermetically sealed in a housing, a condenser, an evaporator, and interconnecting conduits, in combination, said condenser, said evaporator, said interconnecting conduits, and part of said housing con-

sisting of indented portions of a single pair of metal sheets welded together in face-to-face relationship, said pair of sheets being bent at a right angle, the sheet portion forming said condenser 5 extending in parallel relation to one of the vertical walls of the cabinet, and the sheet portion forming the evaporator extending horizontally and projecting through said vertical cabinet wall into the upper portion of said cooling chamber.

10 6. In a refrigerating apparatus of the compression type having a motor-compressor set sealed in a housing, a condenser, an evaporator, and interconnecting conduits, a single pair of metal sheets sealed together in face-to-face relationship 15 and having indentations and corrugations forming a substantial portion of said housing, said condenser and said evaporator, said pair of sheets having a reduced cross section between said evaporator and said condenser as compared with 20 the cross section in other parts of said sheets so as to impede the transfer of heat from said condenser to said evaporator.

25 7. In a refrigerator according to claim 5, said pair of metal sheets having a cut-out recess near the bend between said horizontal sheet portion forming the evaporator and said vertical sheet portion forming the condenser, said recess being arranged within said cabinet wall so as to impede a heat transfer from the condenser into said 30 cooling chamber.

35 8. In a refrigerator having a compressor in a pressure-tight housing, a condenser, an evaporator, and interconnecting conduits arranged to form a refrigerant circulation system, in combination, a pair of metal sheets of elongated shape

welded face-to-face together, each having indentations in registry with indentations of the other sheet, said indentations forming said condenser, evaporator and conduits, at least one of said sheets having another indentation forming part 5 of said housing, said indentations which form said condenser extending laterally over the major portion of the width of said pair and having a longitudinal extension larger than said lateral extension so as to form an extensive flat vessel, 10 said housing and said evaporator being arranged at opposite sides of said condenser near the ends of said oblong and connected with each other by a suction duct forming part of the aforesaid conduits and extending between said condenser and 15 a longitudinal edge of said oblong.

9. In a refrigerator having a sealed motor-compressor set containing an oil pump, in combination, a pair of metal sheets welded together in face-to-face relationship and having an indented area forming a housing for said motor-compressor set, corrugations forming an air-cooled oil circulation conduit outside said housing for connecting said pump with the top portion of 20 said housing, and another indented area forming 25 a condenser for the compressed refrigerant.

10. In a refrigerator having a sealed motor-compressor set containing an oil pump, in combination, a pair of metal sheets welded together in face-to-face relationship and having an indented area forming a housing for said motor-compressor set, and a second indented area surrounding said first area and forming a condenser. 30

RUDOLF HINTZE. 35
